UNITED STATES PATENT OFFICE.

CHARLES W. HALL, OF WAKEFIELD, AND FRANK E. WHEELER, OF BELMONT, MASSACHUSETTS, ASSIGNORS TO HENRY F. MILLER & SONS PIANO COMPANY, OF BOSTON, MASSACHUSETTS, A CORPORATION OF MASSACHUSETTS.

BRACKET FOR GRAND-PIANO ACTIONS.

1,391,054.

Specification of Letters Patent. Patented Sept. 20, 1921.

Application filed January 15, 1921. Serial No. 437,384.

To all whom it may concern:

Be it known that we, CHARLES W. HALL, a citizen of the United States, residing at Wakefield, county of Middlesex, and State 5 of Massachusetts, and FRANK E. WHEELER, a citizen of the United States, residing at Belmont, in the county of Middlesex and State of Massachusetts, have invented new and useful Improvements in Brackets for Grand- 10 Piano Actions, of which the following is a specification.

This invention relates to an improved bracket for grand piano actions.

Grand piano actions are mechanisms of 15 great delicacy and precision and these actions are supported upon two wooden rails, namely, a hammer supporting rail and a wippen rail, the rails being supported upon a series of brackets, these rails being made 20 of wood are liable to swell and shrink, thus changing the position of certain pivots of portions of the action relatively to each other. The slightest change in the relative locations of these pivots makes a difference 25 in the delicacy and perfection of the operation of the grand piano action which is very perceptible to the pianist. It is very desirable, therefore, that the hammer supporting rail and the wippen rail should be firmly 30 supported adjacent to their rear faces but allowed to expand freely in one direction, namely away from their rear faces.

To these ends the invention consists in a bracket formed as hereinafter set forth in a 35 manner described in the following specification and particularly pointed out in the claims.

Referring to the drawings:

Figure 1 is a side elevation of a grand 40 piano action with our improved bracket embodied therein, the key being shown in raised position and the different parts of the actions being shown in their relative positions when the key is so raised.

Fig. 2 is a side elevation similar to Fig. 1 illustrating the key depressed and the different parts of the action in their relative positions assumed just before the hammer strikes the string.

Fig. 3 is a sectional elevation viewed from the right of 3—3, Fig. 1.

Fig. 4 is a detail side elevation of the bracket.

Fig. 5 is a detail plan view of a portion of

the hammer flange rail with a plurality of 55 hammer shank flanges thereon.

Fig. 6 is a detail sectional elevation taken on line 6—6, Fig. 5, illustrating a hammer shank flange and stop.

Fig. 7 is a detail rear elevation of a portion of the wippen rail and flange.

Like numerals refer to like parts throughout the several views of the drawings.

In the drawings, 10 is a bracket embodying our invention. Said bracket consists of 65 a body portion 11, a horizontally extending arm 12 located at the upper end and front of said bracket and a vertically extending arm 13 located adjacent the lower end of said bracket and at the rear thereof. The 70 front edge 14 of said bracket adjacent to the arm 12 extends downwardly and is inclined forwardly from the rear end of said arm. A hammer flange rail 15 is fastened to the underside of the arm 12 by a screw 16. 75 The rear face of the hammer flange rail 15 bears against the inclined front edge 14 of the bracket 10, so that said hammer flange rail is free to expand or swell forwardly and downwardly but the rear face thereof and 80 the upper face thereof are held rigidly positioned against the front edge 14 and the underside of the arm 12. A wippen rail 17 is fastened with its rear face against the front face of the vertical arm 13 by a screw 18, so 85 that the wippen rail is free to expand forwardly but its rear face is rigidly positioned against the front face of the vertical arm 13.

It will be understood that in the action, as a whole, there are a series of brackets 10 90 to which the hammer flange rail and the wippen rail are fastened in the manner hereinbefore described.

19 is a hammer fast in the usual manner to a hammer shank 20 which is pivoted at 95 21 to a hammer shank flange 22, which is fastened in the usual manner to the hammer flange rail 15 by a screw 23. The front end of the hammer shank rests upon a hammer rail 24. 25 is a key pivoted in the usual 100 manner at 26 and having a capstan screw 27 extending upwardly therefrom and engaging a support 28 which is pivoted at 29 to a wippen flange 30 which is fastened by a screw 31 to the wippen rail 17. A repetition lever 32 is pivoted at 33 to an arm 34 on the support 28. A jack 35 is pivoted on the support 28 at 36. A regulating but-

ton 37 is supported upon a regulating rail 38 fast to the bracket 10.

The operation of the piano action is understood by those skilled in the art. Briefly 5 described this operation is as follows: When the key 25 is depressed at its forward end, the capstan 27 moves the support 28 upwardly from the position illustrated in Fig. 1 to the position illustrated in Fig. 2, bringing the outer end of the repetition lever 32 against a stop 39 which consists of a screw having screw-threaded engagement with the hammer shank flange 22. When this occurs the hammer 19 has not yet struck the string 15 40 although very near it and upon a slight movement further of the key downwardly the hammer will be caused to move up into contact with the string by the upper end of the jack 35 which engages a roll 41 on 20 the underside of the shank 18. The outer end of the arm 42 on the jack 35 then engages the regulating button 37 which tips the jack 35 upon its pivot 36, thus causing the upper end of the jack to move to the 25 right, Fig. 2, and release the hammer by slipping out from under the roll 41, so that the hammer will fall back and will not stay in engagement with the string 40 even though the key 35 be held down.

30 From this description it will be seen that a slight change in position of the hammer shank pivot 21 relatively to the supporting pivot 29 will cause a change in the operation of the action, especially as to the particular time when the hammer will engage the string and be released from contact therewith.

By supporting the hammer flange rail 15 upon the bracket in the manner hereinbefore described, it will be seen that the rear face and upper face of said hammer flange rail will remain fixed in position even though the rail itself swells or shrinks, said rail being free to swell downwardly or forwardly. The same is true in relation to the wippen rail which is free to swell but which is positioned fixedly against the front face of the vertical arm 13, so that the pivots 21 and 29 and the stop 39 are always positioned accurately with relation to each other, whereby a much more accurate and delicately adjusted and positioned grand piano action is obtained.

We claim:

55 1. A bracket for a grand piano action embodying a horizontally and forwardly extending arm at the upper end and front thereof and a vertically extending arm ad-

jacent the lower end and rear thereof, a hammer flange rail fast to the underside of 60 said forwardly extending arm and a wippen rail fast to the front edge of said vertically extending arm.

2. A bracket for a grand piano action embodying a horizontally and forwardly 65 extending arm at the upper end and front thereof, the front edge of said bracket adjacent to said arm extending downwardly therefrom and a hammer flange rail fast to the underside of said arm and bearing 70 along its rear face against said front edge.

3. A bracket for a grand piano action embodying a horizontally and forwardly extending arm at the upper end and front thereof, the front edge of said bracket adjacent to said arm extending downwardly therefrom and being inclined forwardly from the rear end thereof and a hammer flange rail fast to the underside of said arm and bearing along its rear face against said 80 inclined front edge, whereby said flange is allowed to expand forwardly while its rear face is fixedly positioned.

4. A bracket for a grand piano action embodying a vertically extending arm ad- 85 jacent the lower end and rear thereof, a wippen rail and means to hold the rear face of said wippen rail in fixed position against the front edge of said vertically extending arm while allowing said wippen rail to ex- 90 pand forwardly.

5. A bracket for a grand piano action embodying a horizontally and forwardly extending arm at the upper end and front thereof and a vertically extending arm ad- 95 jacent to the lower end and rear thereof, the front edge of said bracket adjacent to said horizontally extending arm extending downwardly therefrom, a hammer flange rail fast to the underside of said arm and bearing along its rear face against said front edge and a wippen rail and means to hold said wippen rail in fixed position against the front edge of said vertically extending arm, whereby said rails are allowed to ex- 105 pand forwardly while their rear faces are fixedly positioned.

In testimony whereof we have hereunto set our hands in presence of two subscribing witnesses.

CHARLES W. HALL.
FRANK E. WHEELER.
